UNITED STATES PATENT OFFICE.

JOSEPH SACHS, OF HARTFORD, CONNECTICUT.

QUICK-OPENING SAFETY SWITCH.

Application filed January 25, 1922. Serial No. 531,580.

To all whom it may concern:

Be it known that I, JOSEPH SACHS, a citizen of the United States, residing at Hartford, in the county of Hartford and State of Connecticut, have invented a new and useful Improvement in Quick-Opening Safety Switches, of which the following is a specification.

This invention relates to the operating mechanism of quick opening electric switches of the safety type. Switches of this type are enclosed in metallic boxes and the movable conductors are commonly engaged with and disengaged from the fixed contacts by means of crank spindles that extend through the box walls and on the outside have operating handles.

The object of the present invention is to provide a very simple, cheap, durable and efficient operating mechanism for such switches which will throw the movable conductors very quickly when the handle is turned for opening the circuit and which is so constructed that the parts may be securely locked when the circuit is open.

This object is attained by an organization which has but three essential elements, the crank spindle, the operating handle mounted on and having a lost motion engagement directly with the spindle, and a spring connected between the spindle and handle in such manner that its normal tension holds the handle firmly and when the handle is turned for opening the circuit its tension is increased as the lost motion is taken up so that when the handle positively engages and turns the spindle and starts the movable conductors from the fixed contacts, the spring will then act to throw the movable conductors open very quickly. For locking the parts the handle hub is recessed and a perforated plate is fixed to the box so as to extend over the hub with the openings in the parts in such relation that a lock or seal may be passed through them and the handle hub prevented from turning.

In the accompanying drawings Figure 1 shows a plan of a safety switch, with the cover omitted, provided with an operating mechanism which embodies this invention. Fig. 2 is a section on the dotted line 2-2 on Fig. 1. Fig. 3 is an elevation looking toward the handle side of the box. Fig. 4 on larger scale, shows the connection between the crank spindle and the handle hub.

Fig. 5 is a section on the dotted line 5-5 on Fig. 4. Fig. 6 is a section showing an equivalent arrangement of the connecting spring. Fig. 7 is a view looking toward the side of the modified form.

The box 1 usually made from sheet metal may be any desired size and shape. The switch base 2 of the usual insulating material is shown as fastened to the bottom of the box and mounted on this base there are indicated two fixed terminal contacts 3 and two pivoted conductors 4 of common form, the latter being connected with enclosed fuses 5 in a well known manner. Attached to the movable conductors are insulating plates 6 that have notches 7 through which the crank spindle 8 passes. One end of the crank spindle is pivotally mounted in the side wall 9 of the box and the other end extends through the side wall 10 and a supporting plate 11 that is fixed to the outside of this wall.

The hub 12 of the handle 13 is rotatably fitted on the outer end of the spindle between the side wall of the box and the plate 11 fixed thereto. The handle hub extends through the box wall and on the interior it has a radial slot 14 through which the bent arm 15 of the crank spindle passes. The walls 16 and 17 of the slot are some distance apart but are adapted to be engaged with the crank spindle when the handle is turned a sufficient distance, in other words there is a lost motion connection between the handle hub and the bent crank arm of the spindle so that while the handle is loosely connected with the spindle it will engage and rotate the spindle when turned far enough to take up the lost motion.

In the organization first illustrated a spiral spring is passed around the handle hub and one end is fastened to the hub by a screw 19 and the other end is looped around the spindle. This spring is arranged so as to normally hold the wall 16 of the slot in the handle hub in engagement with the spindle. The tension of the spring retains the handle firmly in the position which it occupies. The parts are shown in the drawings with the circuit closed. When the handle is turned for opening the circuit the friction of the engagement of the movable conductors with the fixed contacts holds the former and the crank spindle while the wall 16 of the handle hub is moving away from the spindle.

the spindle and the wall 17 is moving toward the spindle. During this period the tension of the spring is being increased. When the handle has been turned so that the wall 17 engages the spindle, the spindle is positively turned so as to start the movable conductors from the fixed contacts. After the movable conductors have been started the spring throws the movable contacts open 10 violently and at the same time turns the spindle back against the wall 16 of the hub.

Instead of placing the spring around the outside of the handle hub, as above set forth, it may be arranged inside of the hub. In 15 this case a socket 20 is formed in the outer side of the hub and a coiled spring 21 placed therein with one end of the spring extending into a radial slot 22 in the hub and the other end extending into a diametrical slot 23 in 20 the end of the spindle. The action of the spring in this case is the same as previously described.

The supporting plate fastened to the outside of the box may be provided with perforations 24 and the outer side of the handle hub may be provided with grooves 25, the perforations and grooves being so located that when the switch is opened they coincide and allow the insertion through them of the 25 loop of a lock or seal. A perforated disk 26 may be located between the hub and the plate and fastened to the hub to make the locking of the parts more secure.

The invention claimed is:—

35 1. A switch mechanism comprising a casing, a spindle, a handle hub rotatably fitted on the spindle and extending through the side wall of the casing, and having a lost motion engagement with a bent portion of the spindle within the casing, and a spring connected between the handle hub and the spindle, whereby when the handle is turned the spring is first made tense, then the hub 40 positively engages directly with and moves the spindle, and finally the spring throws the spindle.

2. A switch mechanism comprising a casing, a crank spindle extending through the casing, a handle hub rotatably fitted upon 45 and having a lost motion but positive engagement with the crank spindle within the casing, and a spring connected to the handle hub and the spindle, whereby when the hub is turned the spring is tensioned and then the hub positively engages and turns the spindle.

3. A switch operating mechanism comprising a crank spindle, a handle hub rotatably fitted upon the crank spindle and having a lost motion engagement with a bent portion thereof, and a spring extending around the handle hub and having one end fastened thereto and the other end attached to the spindle.

35 4. A switch operating mechanism for

safety switches comprising a crank spindle, a handle hub rotatably fitted upon and having a lost motion positive engagement directly with the spindle, a spring connected between the handle hub and the spindle, and means for locking the hub against movement.

5. The combination with the enclosing case of a safety switch of a crank spindle, a handle hub rotatably mounted on the spindle and having a lost motion engagement therewith, a spring connection between the handle hub and the spindle, and a plate fitted upon the end of the spindle outside of the handle hub and fastened to the case, the handle hub and plate having openings so related that they may receive locking means.

6. The combination with the enclosing case of a safety switch, of a crank spindle 8 extending through the wall of the case, a handle rotatably mounted on the spindle outside of and extending into the case and having a lost motion engagement directly 9 with a bent portion of the crank spindle inside of the case, and a spring connected between the handle and spindle inside of the case.

7. The combination with the enclosing case of a safety switch of a spindle, a handle hub mounted on and rotatably connected with the spindle outside of the case, and a plate permanently fixed to the case and extending over said hub, said plate and hub having means whereby said plate and hub 10 may be temporarily locked together.

8. A switch operating mechanism comprising a casing supporting a rotatably mounted switch operating crank spindle adapted to be engaged with a switching member, a handle hub extending through the casing, said hub and spindle having substantially coincident axes of rotation with a direct lost motion engagement within the casing between the hub and bent section of the crank spindle and a spring with one end 11 engaging the hub and the other end engaging the spindle.

9. An enclosed externally operated switch comprising a casing, co-operating stationary and movable switching conductors within the casing, a crank extending within the casing and engaging with the movable conductors, a hub provided with handle means and rotatably mounted with its axis substantially coincident with the axis of the crank, said handle hub having a direct lost motion engagement with an angular section of the crank, and a spring connection between the hub and crank.

10. An enclosed externally operated switch comprising a casing, stationary and movable switching conductors within the casing, switch operating means including a handle hub, a plate extending adjacent to said hub,

said plate and hub having means whereby the plate and hub may be locked together to prevent the operation of the switch.

11. An enclosed externally operated switch comprising a casing, stationary and movable switching conductors within the casing, a

movable conductors, a handle hub engaging and adapted to move the crank, and a plate extending adjacent to said hub, said plate 10 and hub having means whereby the plate and hub may be locked together to prevent the movement of the hub.

JOSEPH SACHS.
